[57] CLAIM

The ornamental design for a toilet tank dispenser, as shown and described.

DESCRIPTION

FIG. 1 is a perspective view of a toilet tank dispenser showing my new design, the broken-line showing of the hanger bracket being for illustrative purposes only and forming no part of the claimed design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and

FIG. 7 is a bottom plan view thereof.

FIG. 1

FIG. 2

FIG. 3
